(57) **CLAIM**

The ornamental design for a lumbar stretcher, as shown and described.

DESCRIPTION

FIG. 1 is a perspective view of a lumbar stretcher, showing my new design;

FIG. 2 is a perspective view showing the design in the using configuration thereof;

FIG. 3 is a perspective view of a disassembled state thereof;

FIG. 4 is another perspective view of a disassembled state thereof;

FIG. 5 is another perspective view thereof;

FIG. 6 is a front view thereof;

FIG. 7 is a rear view thereof;

FIG. 8 is a left side view thereof;

FIG. 9 is a right side view thereof;

FIG. 10 is a top plan view thereof;

FIG. 11 is a bottom plan view thereof; and,

FIG. 12 is a perspective view in the open configuration thereof.

The broken line showing ofthe lumbar stretcher is for the purpose of illustrating article and forms no part of the claimed design.

1 Claim, 12 Drawing Sheets
